UNITED STATES PATENT OFFICE.

JOHANNES B. SYLVAN, OF COLUMBIA, SOUTH CAROLINA.

DESIGN FOR A FRATERNAL CHARM OR SIMILAR ARTICLE.

Application filed February 24, 1927. Serial No. 20,871. Term of patent 7 years.

To all whom it may concern:

Be it known that I, JOHANNES B. SYLVAN, a citizen of the United States, and a resident of Columbia, in the county of Richland and State of South Carolina, have invented a new, original, and ornamental Design for Fraternal Charm or Similar Article, of which the following is a specification, reference being had to the accompanying drawing, forming a part thereof, in which—

I claim:

The ornamental design for fraternal charm or similar article, as shown.

Signed at Columbia, South Carolina, this 14th day of February 1927.

JOHANNES B. SYLVAN.
